UNITED STATES PATENT OFFICE.

JOSEPH T. CRAW, OF JERSEY CITY, NEW JERSEY, AND FREDERICK L. SCHLEY, OF NEW YORK, N. Y.

COMBINED DUST-CAP AND WATERPROOF HAT-SHIELD.

1,160,049.

Specification of Letters Patent.

Patented Nov. 9, 1915.

Application filed August 27, 1914. Serial No. 858,833.

To all whom it may concern:

Be it known that we, JOSEPH T. CRAW, a citizen of the United States, and a resident of Jersey City, in the county of Hudson and State of New Jersey, and FREDERICK LUDWIG SCHLEY, a citizen of the United States, and a resident of the city of New York, borough of Brooklyn, in the county of Kings and State of New York, have invented a new and Improved Combined Dust-Cap and Waterproof Hat-Shield, of which the following is a full, clear, and exact description.

This invention relates to wearing apparel, and has particular reference to head coverings.

Among the objects of the invention is to provide a device of the character indicated which is of a light, and preferably cheap, material, adapted for either a dust protector for the head, as may be used when traveling, or to be applied as a shield for a hat, to protect the same from moisture or the like.

Another object is to provide a device of the character mentioned which may be of a nature adapting it to fold into small compass and to be carried readily in the inside of the crown of one's hat, where it will be easy of access when required.

A still further object is to construct a head covering of the nature stated, of a material adapting it to be stamped or printed so as to simulate the appearance of a hat in connection with which it may be worn.

The foregoing and other objects may be carried out in a preferred manner by the devices hereinafter more fully described and claimed, and illustrated in the accompanying drawings, in which—

Figure 1 is a plan view of the crown side or band-blank after being cut and creased; Fig. 2 is a plan view indicating the manner of forming the top of the crown and the rim from a single piece of material; Fig. 3 shows the rim after being folded twice, ready to be placed between the other parts of the structure in folded position; Fig. 4 is a view of the folded crown; Fig. 5 is a plan view showing the parts assembled in folded position ready to be inserted into the top of the crown of the hat; Fig. 6 is a vertical, sectional view of a hat, indicating the location of the attachment in the top of the crown thereof; Fig. 7 shows a hat with our improvement applied thereto; and Fig. 8 is a sectional detail indicating a portion of the

hat in elevation, and a portion of the protector applied thereto in section.

The several parts of the device may be made of any suitable materials, and the relative sizes and proportions thereof, as well as the general design of the mechanism, may be varied to a considerable extent without departing from the spirit of the invention hereinafter claimed.

By way of illustration of a preferred embodiment of the invention, we show a straw hat H, having a ventilated crown C, a band B, and a rim R. This hat will be recognized as of a well known or conventional type, and the covering or protector attachment illustrated is shown as following the type or style of hat set forth. We wish it to be understood, however, that in practice the protectors will be formed and stamped in various styles, as well as sizes and shapes, to accord with the hats for which they are intended.

Referring first to the crown construction, which is adapted to be used either alone as a dust-cap, or in connection with the rim construction as a hat protector, we show in Fig. 1 a cut and scored blank 10. In the formation of this blank from a single strip of material rectangular in form, and by any suitable machine, we provide a series of V-shaped slits 11, arranged vertically downwardly at what becomes the upper portion of the crown, and the points of these slits 11 are connected by a continued series of scores 12. At the bottom of the blank are formed a series of slits 13, the upper ends of which are connected by a continued series of scores 14. Another series of scores 14' may be formed across the flanges determined by the slits 13 and arranged parallel to the scores 14. Each slit 11 is connected to the slit 13 below it by a score 15. Any suitable number of pairs of these slits 11 and 13 may be provided. We find, however, that the preferred number is eight, forming the hat crown, when finished, into an octagonal form, as indicated by reference to Figs. 2 and 7. Each of the eight faces into which the crown side or band is formed represents, therefore, a rectangle bounded on the sides by scores 15, and on the top and bottom by the scores 12 and either 14 or 14', depending upon the height of the crown of the hat. The remaining portion 16 of the base flange between adjacent slits 13 is adapted to be deflected outwardly, bending for this

purpose around the line 14 or 14', as the case may be, during the formation of the crown.

The crown band or side may be regarded as consisting of eight panels, by reason of the construction above described, each panel having attached to its upper end a flange 17, which is adapted to be bent inwardly therefrom around the axis or score 12, and having a bottom or base flange 16. In the formation of this blank into tubular form during the assemblage of the crown, we prefer to make the joint in the midst of one of the panels, and hence we apply gum at one end, as shown at 18. The other end or part of the same panel at the other end of the blank is enough longer than the hat panel to receive the gummed portion thereupon when the two end quarters of the blank are folded inwardly toward each other around the lines *a* and *b*, the gummed portion being placed directly upon the ungummed opposite end.

After the tube has been formed, the same is slipped downwardly over a form, which causes the bottom flanges to be turned outwardly, and thereafter the flanges 17 are bent inwardly on top of the form, the V-shaped slits 11 allowing the edges to lie flat upon the top of the form and without overlapping one another.

Fig. 2 indicates the manner of forming the top of the crown and the rim of the protector. The crown top 19 is substantially octagonal in form, and corresponds in size, as well as shape, to the top of the form above described, and is pasted upon the upper surfaces of the flanges 17 while they lie flat upon the top of the form. The notches 20' formed coincidentally with the tabs 20 are negligible so far as the top of the crown is concerned, being practically invisible in the finished article. The rim structure 21 shown in folded position in Fig. 3, is preferably of a single thickness of material as it is cut from the blank of the crown top 19.

Referring again to the crown portion, after it is removed from the form, a hand-controlled spreader is introduced thereinto, which acts against the crown panels at what might be considered the top of the hat, forming the two creases 22 extending across the front and rear of the crown a short distance below the level of the creases 12. This spreader determines a series of short, diagonal scores or creases 23, and longer creases 24, all of which radiate from the ends of the horizontal scores 22, and at the same time, vertical scores 25 are formed, leading downwardly from said central points at the ends of the scores 22 to the base of the crown. After this spreader is removed from the crown, the crown may be readily folded by drawing apart with one's fingers upon the side portions of the bottom of the crown, a

movement which causes the front and rear portions of the bottom to fold inwardly toward each other upon the top of the crown. Because of the ellipticity of the crown, these end portions will then be 70 spaced slightly from each other. The crown is then folded as indicated in Fig. 4, one end upon the other, into neat form.

As indicated in Fig. 5, the rim structure 21 is adapted, while folded into quarters, 75 as shown in Fig. 3, to be sandwiched between the two parts of the crown, the corners which would otherwise project therefrom being flexible enough to turn over and be there secured by any suitable form of slide- 80 able fasteners 26. We prefer to use at least three of these fasteners, the same being applied to the folded construction as shown in Fig. 5 for at least two purposes; first, to hold the parts together with the rim portion 85 within the crown, and secondly, to cooperate with the inner surface of the hat crown to hold the protector in the top of the crown when not to be used otherwise. The better 90 grades of hats are usually provided with linings L, which are ordinarily held in place without special attachment, by means of the sweat-band 7. The lining L may be easily removed, and the package shown in Fig. 5 put in place, and when the lining is replaced, 95 it will hold, under ordinary circumstances, the package in place, as shown in Fig. 6. If, however, no lining is used in the hat, or if the lining, when used, should prove inefficient to hold the package in place, several 100 or all of the slideable fasteners 26 may be shoved readily outwardly so as to grip the inner surface of the hat crown near the top, as indicated at 27. These fasteners are made 105 preferably of spring material, and have sufficient frictional grip upon the package to cause the outer ends of the fasteners to maintain their grip upon the hat crown.

In the use of this device as a skull-or-dust-cap, as when traveling in a railway train or 110 the like, the crown portion alone is preferred to be used. In order to open it out for use, the steps referred to above for the folding will be reversed, and the cap slipped upon the head. The base flanges 16 ordinarily 115 will naturally assume a position turned upward around the lines 14, and against the outer surfaces of the crown panels, this action of the flanges being due to the application of the device to the round- 120 ed surface of the head.

If the device is to be used as a hat protector in the case of a sudden shower or the like, the crown portion will be opened out and slid directly downward over the hat- 125 crown, the bottom flanges 16 coming adjacent the hat rim R. The rim portion 21 is then slipped down over the crown, the straight edges 28 on the inner margin thereof coming naturally opposite the panel por- 130

tions of the crown. The tabs 20 will turn up slightly, due to the friction of the crown panels, and will occupy an upturned position as indicated in Figs. 7 and 8. The 5 fasteners 26 now come into use to secure the protector members to the hat rim, and at least one portion of each fastener is perfectly long enough to reach far enough inwardly to embrace the crown base flange 16; 10 see Fig. 8.

A device made in accordance with this invention is neat in appearance, having practically none of the unsightly features of hat coverings or protectors heretofore proposed. At any time, either before or after the protector members are made up in the manner above set forth, the material thereof may be printed, stamped, or otherwise decorated to simulate the construction of the 20 hat with which it is to be used. As indicated best in Fig. 8, the crown portion 10 of the protector is marked to indicate a straw-hat crown, having a representation of a band applied thereto. These decorative 25 features may preferably be applied by a suitable indelible ink, which, together with the protector as a whole, will be waterproof.

We wish it to be observed also that while 30 the crown and rim portions are preferably made and sold as separate elements, but for joint use, the arrangement and construction

are such that any individual, if he wishes to do so, may gum or otherwise secure these two parts together, the tabs 20 serving to 35 strengthen the union in connection with the overlapping parts of the rim and crown flanges.

We claim:—

A device of the character set forth comprising a crown member having a tubular band formed vertically into a series of similar panels, having inwardly projecting flanges at their tops and outwardly projecting flanges at their bottoms, with the bottom flanges transversely scored intermediate their ends whereby the height of the tubular band may be varied, a closure member for the top of the band adapted to coöperate with the top flanges, and a rim member having a central opening corresponding in size and shape to the tubular band and adapted to be slipped downwardly over said band to engage upon the outwardly projecting bottom flanges. 55

In testimony whereof we have signed our names to this specification in the presence of two subscribing witnesses.
